7 Wheatfield with crows

*Artist: Van Gogh *Production Year: 1890, Type: Oil painting *Size: 301 x 51 cm *Place: Amsterdam Municipal Museum
*Explain: It was painted in July 1890, just before Van Gogh committed suicide, and is one of his most famous paintings. The dark, low sky, the ominous swarms of crows, and the three crossroads, which do not know where to go, seem to strongly symbolize his despair just before his suicide. "This is a depiction of a huge wheat field under an angry sky, and I tried to express the sadness and extreme loneliness in it," he wrote.

14 Lane of Poplars at Sunset

* Painter: Vincent Van Gogh * Production Year: 1890 * Type: Oil painting * Size: 30.5 x 38.5 cm * Place: Van Gogh Museum
* Explanation of Works: Gogh's relatively early work, mesmerized by popla's sunset, walked on Garosugil countless times. From the old woman's bent figure, she expressed her perspective to connect human life with the twilight and the reddish leaves of autumn. The poplar trees on the right and left, where the old woman stands are described as nature's friends who face each other for a long time of tumult.

16 La méridienne ou la sieste (d'après Millet)

*Artist: Vincent van Gogh * Production Year: 1890-90 * Type: Oil painting * Size: 93 x 73 cm * Place: Orsay Art Museum

*Explaining: This is a replica of Millet's work, and he produced a series of 'four moments of the day,' of which Van Gogh brought the motif from his 1866 work, "The midday." To Theo, "I'm using a different color of language than Millet to express the impressions of light and darkness in black and white. Drawing farmers at work," he said, and saw it should be the subject of modern art.

13 The Mulberry Tree

*Artist: Van Gogh *Production Year: 1889 *Type: Oil painting *Size: 54.6 x 55.0 cm *Place: Norton Simon Art Museum

*Explanation of Works: In the spring of 1889, at the Saint-Léonard de Hospital, his work moved away from the hallucinogenic colors in Arles and developed a more intense brushstrokes into the free, textual coloring. Here, the burning leaves of mulberry trees and the flowing sky and mountainsides are painted so richly. He was particularly satisfied with the painting, writing to Theo in a letter, "It's the most successful."

20 Still Life with Bible

*Artist: Van Gogh *Production Year: 1889 *Type: Oil painting *Size: 39.5 x 48.2 cm *Place: Van Gogh Museum

*Explanation of Works: Van Gogh's father was a Protestant pastor who completed the work months after he returned. At first glance, the canvas reminded me of a still life painting of the 17th century, adding a yellow tone of lemon to a black background with a yellow-brown foreground. On the work, his brother Theo said the color was too dark and gloomy mixed with black, and recommended that he try using a bright and light tone, which later turned it into a bright color.

24 Self-Portrait with Bandaged Ear

*Artist: Vincent Van Gogh *Production Year: 1889 *Type: Oil painting *Size: 73.5 X 92 cm *Storage: Courtauld Art Museum
*Explain: He would have painted more self-portraits than Rembrandt, who is known as the most prolific painter of self-portrait. As such, he seems to have expressed his inner self in painting and used it as a means of communicating with the world. Van Gogh's face, cut off his own ears, looks dark and lonely. His eyes, in particular, look very sad, but he seems to be soothed to some extent, rather than venting his sorrows.

*Artist: Vincent van Gogh * Production Year: 1889-90 * Type: Oil painting * Size: 91 x 73 cm * Place: Orse Art Museum

*Description: This painting is known to have been painted in Antwerp, Belgium, from late 1885 to early 1886. When I passed the Royal Belgian Academy of Art and studied painting for a while, I had a very difficult life during Antwerp with a skull painting based on the basis of painting, but my will to paint was burning, but my mental condition was getting worse.

FIG. 61

31 Ladies of Arles

*Artist: Vincent Van Gogh *Year: 1888 *Type: Oil painting *Size: 73.5 x 52.5 cm *Storage: Hermitage, Hermitage

*Explaining: Van Gogh realized that the ideal painter community he wanted existed only in the ideal way. It expressed complex feelings about frustrated dreams in yellow, green, blue and conspicuous red, which appeared anxious. It also expressed changes in texture, such as impasto technique and direct paint squeezing on canvas, and used decorative short brush touches to further reveal the texture of the surface.

45 The Dance Hall in Arles

* Painter: Vincent van Gogh * Production Year: 1888 * Type: Oil painting * Size: 65 x 83 cm * Place: Orsay Museum

* Explain: This picture is the interior view of the evening at the dance hall Polles-Arlesiennes, where the Japanese style of painting has been involved, making the eyes unusually high, and the hair's curve dominant. Countless characters, adeptly portray the different styles of their clothes and the way people overlap, drawing congestion and saturation.

47 The Starry Night

*Artist: Vincent Van Gogh * Production Year: 1888. Type: Oil painting * Size: 73.7 x 32.1 cm * Place: New York Museum of Contemporary Art

* Explanation of Works: One of Gogh's representative works was painted when he was in a sanremi nursing home after the incident in which he cut off his ears after quarreling with Gauguin. For him, the night sky was the object of expressing infinity, with clouds and atmosphere in the night sky, starlight and moonlight exploding, and the cypress, which stretches vertically high and connects the ground and sky, traditionally symbolized tombs or mourning, but did not ominously see death.

FIG. 95

48 Self - Portrait with Grey Felt Hat

*Artist: Vincent Van Gogh * Production Year: 1887 * Type: Oil painting * Size: 44.5 x 37.2 cm * Storage: Van Gogh Museum

*Explanation of Works: This work depicts the overcoming of Sirea's point-of-view method, which creates delicate expressions with dots, with Gogh's unique rough and powerful short lines. From July 1887, Van Gogh chose inexpensive materials as he began to suffer financially. He sketched the work using red paint and then painted it with a large and small brush touch, creating a rhythmic texture.

FIG. 97

49 Terrace of a café at night

*Artist: Van Gogh * Production Year: 1888 * Type: Oil painting * Size: 10.7 x 65.3 cm * Place: Kröller-Müller Museum

* Explanation: In his letter, he said, "On a blue night, a big gas lamp in the cafe terrace lights up. I can see the starry blue sky above it. Drawing chestnuts right here is amazing. A light white light is the only way to get rid of that night view. The shining square against the backdrop of the Rigo night was painted in bright yellow. Especially the moment I put stars in this night sky was really fun," he wrote.

FIG. 99

60 Flying Fox

*Artist: Van Gogh *Production Year: 1884 *Type: Oil painting *Size: 41.5 cm x 29.6 cm *Score: Van Gogh Museum

*Explaining: This is a kind of tropical bat that is a unique theme for artists. Van Gogh's paintings are based on a rigid, unnatural pose that is stuffed. Van Gogh knew a man who had collected more than 300 rare animals, a bat that may have come from the collection. Van Gogh wanted to portray translucent wings clearly and placed a light source behind him.

51 Pink Roses in a Vase

*Artist: Van Gogh *Production Year: 1890 *Type: Oil painting *Size: 92.6 x 73.7 cm *Place: Metropolis Museum

*Explanation: Just before leaving Saint-Léonard Hospital in May 1890, Van Gogh painted four still-life paintings of both rose and iris in the museum. Consisting of decorative ensembles, such as an early set of sunflowers. Traces of pink and rose petals in the painting, which have faded over time, vaguely conjure up the previously vivid "pink rose bouquet on a yellow-green background in a green vase."

65 Village Street and Steps

*Artist: Van Gogh *Production Year: 1890 *Type: oil painting *Size: 49.8 x 76.1 cm *Place: Saint Louis Art Museum

*Explaining: This work, painted with swirling brush strokes using brilliant colors, looks like everything in the landscape is moving. In this work, brush strokes seem to sweep down the central staircase into all directions of canvas, women sway back and forth as if they were walking down a curved path, and the stairs slide down a hill. The painting was inspired by Ober's old buildings and the countryside around the town where he lived.

FIG. 111

66 Portrait of Adeline Ravoux

*Artist: Van Gogh *Production Year: 1890 *Type: Oil painting *Size: 62.0 x 52.8 cm *Owner: Cleveland Museum of Art
*Explanation of Works: In May 1890, Van Gogh left the South and settled in Auvers, a small town north of Paris, and rented a room at the inn in Arthur Lavus. The portrait is completed in the last few months of the artist's life, depicting Rabus' 13-year-old daughter Adelin. Van Gogh wrote that he wanted his portrait to convey the "passionate aspect" of modern life through "modern taste for color."
